FEED REGULATOR

Willard E. Bassett and Bert L. Bassett,
Detroit, Mich.

Application November 20, 1933, Serial No. 698,903

1 Claim. (Cl. 103—236)

The object of this invention is to provide means for controlling the flow of fuel to the carburetor of an internal combustion engine so that flooding of the carburetor will not be apt to occur and a supply of fuel to the carburetor will be assured as long as the main supply tank contains some fuel. The invention is illustrated in the accompanying drawing and consists in certain novel features which will be hereinafter first fully described and then more particularly defined in the appended claim.

In the drawing,

Figure 1 is a vertical section of an apparatus embodying the invention.

Figure 2 is an end elevation of the same.

Figure 3 is a plan view, partly in section, on the line 3—3 of Figure 1.

In carrying out the present invention, there is provided a pair of cylinders which are connected at their lower ends with the inlet of the carburetor and at their upper ends are connected with the intake manifold of the engine and with the main supply tank. The cylinders consist of open-ended bodies 1 of suitable material having their ends fitted in annular grooves in a top plate 2 and a bottom plate 3, bolts 4 being disposed through the margins of the top and bottom plates and secured by suitable nuts, as will be understood. The bottom plate 3 has ports 5 formed therethrough on the axes of the respective cylinders, and to the underside of the bottom plate is firmly secured a reservoir 6 from which a pipe 7 leads to the inlet of the carburetor. The top plate 2 has ports 8 formed therethrough on the axes of the respective cylinders and these ports may be formed in the ends of suction pipes 9, the ends of which are threaded into the openings in the top plate, as will be understood upon reference to Figure 1 of the drawing. The top plate is further provided with openings, in one of which is secured an air vent nozzle or pipe 10 for each cylinder and the end of a fuel supply pipe 11 which leads from the main fuel tank.

A disk valve 12 is provided to seat in each port 5 in the bottom plate and from said valves depend stems 13 which are pivoted at their lower extremities to opposite ends of a rocking arm 14 which is disposed within the reservoir 6 and is fulcrumed midway its ends upon a lug or bracket 15 provided on the bottom plate 3, as clearly shown in Figure 1. An upper stem 16 rises from each valve 12 and plays in a socket 17 in the lower end of a needle valve rod 18 which is disposed on the axis of the respective cylinder and has its upper end tapered to en-

gage in the port or valve seat 8. The lower end of the valve rod 18 is provided with an annular flange 19 and near the upper extremity of said rod is a similar flange 20, a float 21 being mounted loosely upon the rod between the two flanges, as clearly shown. A guide bracket 22 is preferably provided in the upper end of the cylinder to encircle the upper end of the valve rod so as to hold the same to a rectilinear path in its movements, the stem 16 cooperating with the bracket 10 to this end.

The construction and arrangement of the several parts of the apparatus having been thus made known, it is thought the operation of the same will be readily understood. Initially, one of the cylinders 1 will be filled with fuel and the float 21 in said cylinder will automatically rise with the level of the fuel until it impinges against the flange 20 whereupon it will act to lift the rod 18 and cause its upper end to seat in the port 8 thereby cutting off the suction and further inflow of fuel. The float in the companion cylinder will, of course, be at the lower limit of its movement resting upon the flange 19 and the weight of the float will hold the rod 18 lowered and bearing against the valve 12 so that the valve will be seated in the port 5. The valve in the filled cylinder will, of course, be raised inasmuch as the rocking arm or walking beam 14 rises at one end as it descends at the opposite end and the parts will thus be set in the positions shown in Figure 1 in which flow is established from the righthand cylinder to the carburetor. As the motor operates, suction will be set up through the intake manifold and the suction pipe 9 so that a fresh supply of fuel will be drawn in through the supply pipe 11 to the empty cylinder in which the rod 18 is in its lowered position. Therefore, as the fuel is drawn from one cylinder the other cylinder will be filling and the float 21, in the latter cylinder, will be rising toward the flange 20. The inflow in one cylinder will continue until the outflow in the other cylinder has brought the float in the latter cylinder to rest upon the flange 19, whereupon the weight of the float will cause the rod 18 and the valve 12 to drop so that further flow from the active cylinder will be cut off and the needle valve rod 18 will be unseated so that suction will then occur through the suction pipe 9. When the valve 12, in the one cylinder, seats to cut off the flow therefrom, the valve 12 in the other cylinder will, of course, be raised and it will continue in the raised position until the cooperating float has

been brought down to rest thereon by the diminishing supply of fuel. The air vent 10 provides an escape for air which would otherwise be trapped in the cylinder so that a full supply 5 of fuel may be permitted to enter the cylinder at each operation.

The flow to the carbureter will be due to gravity and the suction through the carbureter and will be free from those intermittent disturbances 10 which are due to possible surging and eddying in the incoming supply. Flooding of the carbureter is, therefore, prevented inasmuch as the carbureter draws its supply from a quiet body of fuel and the flow into the carbureter will at 15 no time be greater than the consumption. As long as the main fuel tank contains fuel there will be a supply immediately available for the carbureter inasmuch as the suction of the motor is drawing fuel at all times into one or the other 20 cylinder. In order to prevent accidental opening of the valves due to jar of the motor or from other causes, there is provided a tensioning device preferably in the form of a spring clip 23 having inwardly directed resilient attaching fingers 24 which fit into suitable sockets in the lug 25 or bracket 15. The bottom of the clip is spaced from the lug 15 and is formed with a depending V-shaped projection 25 which bears against the rocking arm 14 at the pivot thereof, as best shown 30 in Figure 1 of the drawing. The device is exceedingly simple in the construction and arrange-

ment of its parts and is not apt to get out of order. The cost of maintenance is, therefore, very slight and the device will operate automatically and efficiently at all times.

Having thus described the invention, we claim:

In a feed regulator, a pair of receptacles each having an outlet opening in its bottom and an inlet at its top, a container under said receptacles communicating with the receptacles through the openings, valves for closing said outlet openings 10 having stems extending vertically in said container and through the outlet openings into said receptacles, floats in said receptacles directly over said valves for alternately acting upon the valves to close one valve while the other opens, 15 a rocker arm in said container extending between and pivoted to the stems of said valves, a bearing bracket in said container located over said arm and pivoted to the arm intermediate the length thereof to mount the arm for rocking 20 movement, a tooth rising from said arm over its pivot, a lug over said tooth formed with notches in opposite side faces, and a U-shaped spring clip having its arms engaged in the notches of said lug and its bridge portion extending under 25 the lug over said tooth and formed with a depending spur engaging the tooth to yieldably resist rocking of the arm.
